UNITED STATES PATENT OFFICE.

EDWIN H. MARBLE, OF WORCESTER, MASSACHUSETTS, ASSIGNOR TO CURTIS & MARBLE MACHINE COMPANY, OF WORCESTER, MASSACHUSETTS, A CORPORATION OF MASSACHUSETTS.

SEWING MACHINE.

Application filed September 29, 1927. Serial No. 222,893.

This invention relates to that type of sewing machine used in the textile manufacturing industry, commonly known as the "railway sewing machine," used for sewing together ends of bolts of cloth, flour sacks, canvas, harness or other heavy work.

The principal objects of this invention are to provide means for disconnecting the drive and stopping the machine in a readily accessible position where these parts are visible to the operator, so that any threading of the needle or adjustment of the looper can be made readily, and so that if the gear and worm do not come into proper mesh when an attempt is made to start the machine, that fact can be observed readily and corrected; and to provide improved means for automatically stopping the machine at a definite distance after the needle has left the end of the stitching position. Other objects and advantages of the invention will appear hereinafter.

Reference is to be had to the accompanying drawings, in which

Fig. 1 is a sectional view across a machine constructed in accordance with this invention;

Fig. 2 is a plan of the same;

Fig. 3 is a sectional view of part of the mechanism on the line 3—3 of Fig. 2;

Fig. 4 is a longitudinal sectional view showing the means for stopping and starting the machine, taken on the line 4—4 of Fig. 2;

Fig. 5 is a similar view showing the automatic stopping arrangement;

Fig. 6 is a side view of the stopping eccentric; and

Fig. 7 is a plan of the same.

In the type of machine mentioned above, the ends of successive bolts or pieces of cloth or other material are sewed across to attach them together. A sewing mechanism is used for this purpose mounted on a carriage which traverses along a way or frame from selvage to selvage, sewing a single or double thread as desired. When it reaches one end, the machine is drawn back by hand to the starting point at the other side. Several devices have been on the market for this purpose, but as a general thing the drive is through a worm which meshes with a worm gear that, either directly or indirectly, meshes with a secondary screw. The revolution of the screw imparts the necessary motion to the

carriage. The stopping of the mechanism is accomplished by bodily moving the screw away from the worm. If when moved back it does not mesh directly it will bind, and it is necessary to turn it to bring it to proper position.

As heretofore constructed these parts have been under the frame so that the meshing of the screw and worm would not be visible to the operator readily, which introduced quite a handicap to the successful operation of the machine. It is also desirable that the front of the sewing mechanism be exposed so that any threading of the needle or adjustment of the looper can be made readily. This also was detrimental in the old form of machines in which the operating mechanism is located below and covered by the other parts. It is also essential that in the correct operation of the traversing motion of the sewing machine carriage the latter be stopped at a definite distance beyond the point at which the needle leaves the end of the stitching position. It is desirable also that an automatic control be provided for securing this result.

In order to secure these advantages, a machine is shown in the drawings embodying the principle of a sewing machine 10 which is mounted on a carriage 11 and moves across the machine. There is no improvement here in the sewing machine itself. This carriage 11 is mounted on ways 12 in accordance with this invention which support it and guide it accurately across from one side to the other.

The machine is operated by a motor or other means not shown, for driving an endless belt 13 which has a long horizontal loop along the frame and passes over a pulley 14 and under two idler pulleys 15 so as to drive the former, in all positions thereof. This pulley 14 is mounted on a hand wheel 16 which is fixed on a shaft 17 and the belt rotates it.

This shaft is provided with a worm or screw 18 which is shown in mesh with a worm wheel 19 that is fixed on a vertical shaft 20. On the bottom of this shaft is another worm wheel 21 which meshes with a worm or rack 22 extending along the machine in stationary position. The rotation of the shaft 17, therefore, rolls the wheel 21 along this rack.

The shaft 20 is mounted in fixed bearings on the carriage 11. Therefore, the carriage

2
5 moves along during this operation. The sewing machine itself is operated from the motor or other source of power in the usual way by the belt 13 which, on account of extending along the front in a horizontal loop, is always in a position to operate the moving sewing machine. The method of operating the needles of the sewing machine itself from this belt is not shown, as it does 10 not constitute a part of this invention.

15 In order to stop the movement of the carriage the shaft 17 is moved bodily away from the wheel 19. For this purpose this shaft is not mounted in fixed bearings on the carriage 11 but in bearings on a slide 24 which is adapted to move in ways 23 fixed to the carriage 11.

20 The slide 24 is provided with a pair of brackets 25 carrying a pivot stud 26 on which is pivoted a link 27 having a circular recess in which is located an eccentric 28. This eccentric is part of the collar 35. The collar 35 turns on a stud 36 fixed in brackets 30 on the carriage 11. An operating handle 29 is fixed to the collar 35. When this handle is turned up to the position shown in Fig. 4, it turns the collar 35 on the stud 36 and thus through the eccentric 28 and the link 27 draws the carriage 24 back so 30 that the worm 18 is entirely out of mesh with the wheel 19. When the handle is moved down to horizontal position as shown in Fig. 5, the slide 17 is moved up to the position shown in Fig. 2, so that the worm 18 is in 35 mesh with the wheel 19. Should it be desired at any time to stop the movement of the carriage along the ways, for the purpose of readjustment of the needle or rethreading of the same, the handle is readily accessible and can 40 be lifted out of locking position by hand.

45 As long as the handle is horizontal, the carriage will move along until the handle 29 comes into contact with a cam 31 which is adapted to be fixed in adjusted position on the stationary frame 12. This adjustment is secured by the bolt 34, slot 32, and a series of perforations 33. The movement of the end of the handle up the incline draws the slide 24 back sufficiently to disengage the worm 18 from the wheel 19 and stop the 50 machine, although the belt 13 operates continuously.

55 In the operation of the device to sew a lap seam, the end of one piece of cloth is brought around back of the needle under the aim of the sewing machine and placed on pins of the usual construction. The end of the other piece is entered from the front and also placed on the pins. The handle 60 29 is then brought down from the vertical to horizontal position which brings the rotating worm into mesh with the wheel 19. If they do not mesh correctly the operator can see that fact and operates the handle 65 when the worm is rotated around far

enough so that the teeth come into proper mesh. This starts the shaft 20 to rotating and rolls the wheel 21 along the rack until the parts get to the position shown in Fig. 5, at which time the handle 29 moves up the 70 cam 31 and stops the traversing part of the machine. The bringing of the handle up to vertical position merely moves the worm farther away, and the handle is held there by the eccentric construction. 75

In this way it will be seen that the meshing worm and wheel are visible to the operator so that he can bring them into mesh properly and that the front of the sewing machine is exposed so that any threading 80 of the needle or adjustment of the looper can be made readily; there is nothing to obstruct the view of the operator, so that the necessary adjustments can be made very conveniently. Furthermore, it will be seen 85 that as the carriage operates it is stopped at a definite point previously determined by adjustment, and that the stopping is automatic and positive.

90 Although I have illustrated and described only one form of the invention and shown it as applied to a particular type of sewing machine, I am aware of the fact that modifications can be made in these respects without departing from the scope of the invention as expressed in the claims. Therefore, I do not wish to be limited in these respects, but

What I do claim is:

1. In a sewing machine for the purpose 100 described, the combination with a carriage, a stationary rack, and a worm driving device comprising a worm wheel on the top of the carriage, of a slide on the carriage having a shaft thereon, a worm on the shaft meshing with the worm wheel, means for constantly operating the said shaft in all positions thereof, and means for moving the slide back and forth on the carriage to engage and disengage the worm and worm 105 wheel.

2. In a sewing machine for the purpose described, the combination with a carriage, a stationary rack, and a worm driving device comprising a worm wheel on the top of the carriage, fixed ways on the machine for 110 accurately guiding the carriage back and forth, a worm movably carried on the top of the carriage and adapted to be brought in and out of mesh with the worm wheel for 115 bodily moving the carriage, and means for constantly rotating said worm.

3. In a sewing machine of the class described, the combination with a sewing machine proper and a traversing carriage on 120 which it is located, of a driving belt, a pulley engaging the driving belt in all positions of the carriage, a shaft on which the pulley is mounted, a slide on said carriage carrying 125 said shaft, a worm on the shaft, a worm 130

wheel over the carriage adapted to be engaged by the worm when the slide is moved up, means associated with the wheel for traversing the carriage when the worm wheel rotates, and means for automatically moving the slide back when the carriage has reached a predetermined point in its stroke to move the worm out of mesh with the worm wheel.

4. In a sewing machine of the class described, the combination with a sewing machine proper and a carriage on which it is located, of a driving belt, a pulley engaging the driving belt, a shaft on which the pulley is mounted, a slide on said carriage carrying said shaft, a worm on the shaft, a worm wheel adapted to be engaged by the worm when the slide is moved up, and means for automatically moving the slide back when the carriage has reached a predetermined point in its stroke.

5. In a sewing machine for the purpose described, the combination with sewing means and a movable carriage on which it is mounted, of a belt having a horizontal loop extending along the carriage, a shaft in position to be driven by said belt in all positions of the carriage and having means for causing the carriage to move across the machine, a slide on the carriage having bearings for said shaft, a link connected with the slide, an operating handle, and an eccentric on the handle connected with the link whereby the movement of the handle about the axis of the eccentric will move the slide back and forth to connect the carriage with the power and disconnect it therefrom.

6. In a sewing machine for the purpose described, the combination with sewing

means and a movable carriage on which it is mounted, a belt having a horizontal loop extending along the carriage, and a shaft in position to be driven by said belt in all positions of the carriage and having means for causing the carriage to move across the machine, of a slide on the carriage having bearings for said shaft, a link connected with the slide, an operating handle, an eccentric on the handle connected with the link, whereby the movement of the handle about the axis of the eccentric will move the slide back and forth to connect the carriage with the power and disconnect it therefrom, and a cam in fixed position adjustably mounted and so located as to be engaged by said handle at the end of the stroke of the carriage and shaped to lift the handle to turn the eccentric and disconnect the feed.

7. In a sewing machine for the purpose described, the combination with sewing means and a movable carriage on which it is mounted, a belt having a horizontal loop extending along the carriage, and a shaft in position to be driven by said belt in all positions of the carriage and having means for causing the carriage to move across the machine, of an operating handle, means whereby the movement of the handle will move to connect the carriage with the power and disconnect it therefrom, and a cam in fixed position adjustably mounted and so located as to be engaged by said handle at the end of the stroke of the carriage and shaped to lift the handle to disconnect the feed.

In testimony whereof I have hereunto affixed my signature.

EDWIN H. MARBLE.
